UNITED STATES PATENT OFFICE

THOMAS H. SYMINGTON, OF BALTIMORE, MARYLAND, ASSIGNOR TO T. H. SYMINGTON & SON, INC., OF BALTIMORE, MARYLAND, A CORPORATION OF MARYLAND

PLANK OR RAIL FENCE CONSTRUCTION

Application filed July 18, 1929. Serial No. 379,227.

The invention relates to fences, particularly to a plank or rail fence construction, and has for its principal object the provision of a novel fence embodying posts equipped with 5 special means for supporting and holding in secured relation a plurality of planks or bars, it being a feature that the planks or equivalent elements are maintained in uniformly spaced relation so that the fence will 10 have a neat and attractive appearance.

An important object of the invention is to provide a fence construction in which all of the planks, bars or their equivalent are individually held against the posts so that the 15 fence will have great strength and be able to withstand quite a severe strain such as might result from an animal or vehicle running or jumping into it.

Another object is to provide a fence embodying a plurality or series of vertically 20 spaced planks or bars with means for supporting them individually so that in the event of breakage of an upper bar or plank, as might readily occur in hunting country, the 25 person causing the damage may be able to remove a broken top rail or plank and replace it by one of the lower ones so that the value 30 of the fence in preventing escape or straying of the cattle or the like will be practically unimpaired.

A specific object is to provide a fence having a peculiar construction of post and retaining means thereon particularly adapted for use at a gateway where so-called bars are 35 ordinarily used to bridge the space between the posts at opposite sides of the gateway or gap.

An additional object is to provide a fence which will be simple and inexpensive to build, 40 positive in action, efficient and durable in service, and a general improvement in the art.

To the attainment of the foregoing and other objects and advantages, the invention preferably consists in the details of construction 45 and the arrangement and combination of parts to be hereinafter more fully described and claimed, and illustrated in the accompanying drawings, in which:

Figure 1 is a perspective view of a fence constructed in accordance with the invention,

Figure 2 is a view of one of the posts, partly in elevation and partly in section, this view also showing a pair of the top rails or planks in cross section,

Figure 3 is a top plan view of the post 55 alone,

Figure 4 is a fragmentary perspective view illustrating the construction at a gateway or gap, and

Figure 5 is a fragmentary vertical section 60 through a post and cross section through the plank or rail and bar shown in Figure 4.

In carrying out my invention I provide posts 10 which must of course be anchored in the ground at suitable distances apart and 65 which are provided with means for supporting the rails or planks 11 in a manner to be described. Each post is here shown as an elongated body preferably constructed of concrete or cement reinforced in any desired 70 manner as for example by means of a plurality of longitudinally extending rods 12 arranged in any desired manner. The length of the post must of course depend to a certain extent on the contemplated height of the 75 fence and it is equally clear that the intention is to embed a portion of the post within the ground. While it is not necessary the post is shown as slightly tapered, at least in one dimension from the ground line to the 80 upper end. Carried by the post is a series of vertically spaced U-shaped brackets 13 which project beyond one face and which are held in place as by embedding them within the post, the ends being preferably laterally deflected at 14 so as to prevent accidental detachment.

The planks or rails 11 which extend from post to post are preferably of the same length and may very conveniently be rough or 90 finished boards of any preferred dimensions, the common ordinary variety having a width of four to six inches and a thickness of approximately seven-eighths inch being particularly well suited for the purpose. These 95 planks or rails are arranged with their ends in slightly overlapping relation as clearly indicated in Figure 1 with these overlapping ends located within the confines of the brackets 13. Clearly, the individual planks or 100

rails may be simply slid into place in an obvious manner and even without the provision of any further securing means the fence will be adequate for all ordinary purposes. However, in case it is desired to insure that there will be no displacement of the planks or rails, as might result from an animal rubbing against the fence, use may be made of simple or ordinary staples 15 arranged in straddling relation to the upper arms of any or all of the brackets 13 and penetratingly engaging within the planks or rails as clearly shown in the drawings. It is very probably unnecessary to use these staples at all points, it being generally sufficient to provide them in connection with the upper rail or plank only or the upper and intermediate.

The fence is assembled in the manner shown and described and it will be noted that it will present a very neat and attractive appearance with pleasing lines that will not constitute a discordant note in an otherwise pleasing landscape. A distinct feature of advantage is that in the event of breakage of a top rail, as might be caused by the jumping of a horse in a hunting country, the broken rail may be quickly and easily pulled out and replaced by one taken from the bottom part of the fence so that there will be no resultant gap through which cattle or other animals might escape. Owing to the extreme simplicity of the securing means it is apparent that very little labor would be required to effect permanent repairs or replacements.

It is well known that it is a common practice among farmers, agriculturists and others to provide gateways or gaps which are not provided with regular gates but which are closed by so-called bars which bridge the space between the posts at the opposite side of the gateway or gap. In adapting my invention to take care of this feature or contingency, I provide posts 16 similar to the posts 10 and having similar reinforcing elements 17 therein. There would also be a series of vertically spaced substantially U-shaped brackets 18 embedded within and projecting beyond one face of the post with their inner ends curved or deflected at 19 to prevent withdrawal. However, there is a point of difference between the brackets 18 and the above described brackets 13 and that is that the brackets 18 have their arms 20 spaced apart the proper distance to receive a rail or plank 11 between them while at the same time the bight portion is formed with an offset and constricted portion 21 of a size proper to slidably receive a so-called bar 22. In case a gateway or gap is provided there would be one of the posts 16 at each side, the brackets 18 supporting the ends of the planks or rails 11 which may be secured by means of staples 23 of the same character as the staples 15. The desired or proper number of bars 22 are then simply slipped into the offset or con-

stricted portions 21 of the brackets 18 so as to bridge the gap or gateway. Clearly whenever it is desired to open the gateway for any reason, one end of as many of the bars 22 as are provided would simply be slipped out of the constricted portions 21 of the brackets. It will be noted that the posts 16 with the brackets 18 thereon will harmonize perfectly with and have the same general appearance as the ordinary posts 10 with their brackets 13.

From the foregoing description and a study of the drawings it will be apparent that I have thus provided a very simply constructed and inexpensive fence which will possess many features of advantage and superiority over ordinary constructions, particularly in point of strength, uniformity and appearance as well as ready reparability. It is thought that the construction, operation and advantages should be readily apparent to one skilled in the art without further explanation.

While I have shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, I claim:

1. In a fence construction, a post comprising a vertically elongated body, a series of vertically spaced substantially U-shaped brackets secured thereto and projecting beyond one face thereof, planks having their ends engaged within and secured with respect to said brackets, each bracket having its bight portion formed with an offset or constricted portion, and bars slidably received within said constricted portions.

2. In a fence construction, a post provided with a substantially U-shaped bracket projecting beyond one face and adapted to receive one end of a rail, the bracket being further formed with retaining and guide means outwardly of the rail, and a bar removably engaged within said retaining and guide means.

3. In a fence construction, a post provided with a substantially U-shaped bracket projecting beyond one face and adapted to receive one end of a horizontally arranged rail, the bracket having its bight portion formed with an offset of less width than the remainder of the bracket, a securing member straddling one arm of the bracket and engaging the rail, and a bar slidably removably engaged within said offset portion.

4. In a fence construction, a post pro-

vided on one face with a series of substantially **U**-shaped brackets, a rail engaged within each bracket, a second rail disposed within each bracket with its end in overlapping relation to the end of the first named rail, a securing member straddling the upper arm of each bracket and penetrantly engaging within the upper edge of the first named rail, said second named rail being slidable and capable of removal without disturbing the first named rail.

5. In a fence construction, a post provided on one face with a series of substantially **U**-shaped brackets, a rail engaged within each bracket, a second rail disposed within each bracket with its end in overlapping relation to the end of the first named rail, and securing members straddling the upper arms of certain of the brackets and penetrantly engaging within the upper edges of certain of the rails.

In testimony whereof I affix my signature.
THOMAS H. SYMINGTON.
